BLIND STITCH SEWING MACHINE

Charles W. Mueller, St. Louis, Mo., assignor to
 Lewis Invisible Stitch Machine Company, St.
 Louis, Mo., a corporation of Maine

Application July 26, 1937, Serial No. 155,788

12 Claims. (Cl. 112—176)

This invention relates to new and useful improvements in sewing machines generally, although more particularly to sewing machines of the blind stitch type.

5 In blind stitch sewing machines, such as is shown in each of my prior Patents 1,989,602, Jan. 29, 1935 and 2,018,186, Oct. 22, 1935, the reciprocatory ridge forming element is mounted directly below the needle on a work support which is 10 fulcrumed on a horizontal pivot located in rear of the needle path. The ridge forming element which in one form is a disc, is provided with relatively low and high peripheral portions which are alternately positioned in cooperative relation with 15 the needle to form resultant "anchor" and "skip" stitches. The driving connections between the main shaft and the oscillatory shaft which is journaled on the work support and which reciprocates the ridge forming element, is such that when a seam or extremely thick layers of fabrics 20 are fed over the element, the work support will be depressed and the driving connections will cause the oscillatory shaft to rock and thereby shift the ridge forming element out of its true cooperative relation with the needle with the result that one or more stitches will be improperly positioned in 25 the fabric or fabrics.

One of the important objects of this invention is to provide driving connections between the 30 main shaft and the reciprocatory ridge forming element operating shaft whereby the element will remain in its true cooperative relation with the needle when the pivoted work support is depressed and thereby insure the proper positioning of the 35 stitches in the fabric or fabrics.

Another object of the invention is to provide a main frame which includes a standard, a laterally extending upper arm and a forwardly and downwardly inclined arm, a reciprocatory needle 40 and a presser foot mounted on the front end of the forwardly extending arm, and a work support which is fulcrumed on a horizontal pivot located in rear of the needle path, whereby the presser foot will remain at the same height relative to the operator and yet afford increased room under the laterally extending arm for the passage of the work when the work is being fed rearwardly and also when the work is being removed from the machine upon depression of the pivoted work 45 support.

Another object of the invention is to provide manually releasable means for normally locking the work support against abnormal depression to thereby insure proper feed action of the fabrics, 50 yet permitting a slight depression of the work

support to permit not only a variation in the thicknesses of the fabrics being stitched, but also to permit seams being fed over the ridge forming element.

A further object of the invention is to provide 5 manually operable means for varying the initial position of the work support and the ridge forming element which is mounted thereon, relative to the needle in order to set the machine for a predetermined depth of needle penetration in the 10 fabric or fabrics.

With these and other objects in view which will 15 more fully appear, the nature of the invention will be more clearly understood by following the description, the appended claims, and the several views illustrated in the accompanying drawings.

In the drawings:—

Figure 1 is a top plan view of a machine constructed in accordance with my invention,

Figure 2 is a right hand elevation thereof, the 20 standard being shown in section,

Figure 3 is a front elevation thereof,

Figure 4 is a left end elevation thereof,

Figure 5 is a bottom plan view of the machine,

Figure 6 is an enlarged vertical section taken 25 on the line 6—6 of Figure 1, the stitching mechanism being omitted,

Figure 7 is an enlarged detail section showing a slight depression of the work support relative to the needle,

Figure 8 is an enlarged vertical section showing 30 the work support in its locked or normal position,

Figure 9 is a similar view but showing the work support in its unlocked or fully depressed position,

Figure 10 is a view showing the driving connections between the main shaft and the oscillatory shaft which operates the ridge forming element, the view indicating the limits of the oscillatory movements of the element when forming all "anchor" stitches,

Figure 10^a is a view showing the corresponding position of the control lever,

Figure 11 is a view similar to Figure 10 but 45 showing the limits of oscillatory movements of the element when forming alternate "anchor" and "skip" stitches.

Figure 11^a is a view showing the corresponding position of the control lever,

Figure 12 is a plan view of the presser foot and showing the needle, the top feed dog, the ridge forming element, and the work clamp, and

Figure 13 is a top plan view of the left end of the work support showing the ridge forming element, 55

the operating shaft therefor, and the work clamp.

Like reference numerals designate corresponding parts throughout the several figures of the drawings.

5 The sewing machine includes a main frame A which comprises a base 5, a standard 6, an arm 7 which extends laterally from the upper end of the standard and terminates in a forwardly extending arm 8 which is inclined downwardly and 10 forwardly relative to the base, and posts 9, 9 which are integral with the base and are located at the right of the arm 8 but in rear of the forward end thereof.

Rigidly fixed to the forward or free end of the 15 arm 8, is a presser foot B having a centrally located longitudinal opening or slot 10 formed therein, the foot being forwardly and downwardly inclined in a plane disposed in parallelism to the major axis of said arm 8.

20 Journalled in the upper end of the standard 6 and in the arm 7 is a main shaft 11, and journalled in the arm 8 and extending longitudinally thereof is an oscillatory needle shaft 12 having a needle arm 13 fixed to its front end. The needle shaft 12 is located directly above the presser foot opening 10 and has its longitudinal axis in a downwardly and forwardly inclined plane disposed in parallelism with the presser foot. Attached to the needle arm 13 is a curved needle 14 30 which reciprocates across the opening 10 of the foot. The needle shaft 12 is oscillated from the main shaft 11 by connections such as is shown in my prior Patent 2,018,186 referred to above. A looper or spreader 15 cooperates with the needle 14 in the usual manner to form single thread chain stitches, although any other type of complementary stitch forming mechanism may be employed if desired. The looper 15 is fixed to a looper rod 16 which is fulcrumed on a depending 40 arm 17 pivoted on a horizontal pin 18 mounted in the arm 8 and the looper rod is driven from the main shaft 11 by the usual connections.

A work support C is pivoted by bearings 19 to the ends of a horizontal shaft 20 clamped in 45 spaced bearings 21, 21 formed in the posts 9, 9 of the main frame. It will be noted that the pivot shaft 20 is disposed in a plane parallel to the main shaft 11 and that said pivot shaft is located considerably in rear of the needle 14 50 as well as in rear of the front end of the presser foot B. This work support C has its left end reduced to form a horn 22 and projecting laterally from the outer end of the horn is a rectangular frame 23 having an open top and bottom. 55 This frame 23 is located directly under the presser foot B and includes front and rear walls 24, 25 and an end wall 26.

Operating in the presser foot opening 10 for 60 intermittently projecting a node of fabric upwardly into needle penetrating position, is a ridge forming element D which in this instance consists of a disc fixed to an operating shaft 27 which is journalled at the ends in screw bearings 28, 29, the screw bearing 28 being mounted in an 65 opening 30 formed in the end wall 26 of the frame 23 and the screw bearing 29 being mounted in an opening 31 formed in a lug 32 which depends from the under side of the work support C. The oscillatory operating shaft 27 is disposed 70 in a horizontal plane in parallelism not only with the main shaft 11 but also with the pivot shaft 20 of the work support. It will, therefore, be seen that the work support C extends forwardly from the pivot shaft 20 to a point under the 75 presser foot B and that this work support is ca-

pable of swinging downwardly away from the presser foot or upwardly toward the same. It will also be observed that the shaft 27 which operates the ridge forming element D is disposed in front of the pivot shaft 20 and is movable upwardly and downwardly with the work support and consequently when the work support is lowered the ridge forming element D will be correspondingly lowered with respect to the path of the needle. The ridge-forming disc D is formed with a concentric periphery 33 and with a radial front edge 34, and a recess 35 is formed at their juncture, the recess forming a resultant step 36. It will be observed that the concentric edge 33 and the step 36 form peripheral surfaces 15 or portions of different radii which are arranged in tandem, the portion 33 constituting a high portion and the step 36 constituting a low portion. When the high portion 33 is positioned under the needle the latter will form resultant "anchor" stitches in the fabric or fabrics and when the low portion 36 is positioned below the needle, the latter will form "skip" stitches in the fabric or fabrics. In other words, the effective 20 depth of needle penetration in the fabric or fabrics is constant when the high portion 33 is positioned below the needle but when the low portion 36 is positioned below the needle the depth of needle penetration will be decreased, as fully explained in my prior Patent 2,018,186 referred to above.

An upwardly spring pressed work clamp E is mounted on the work support C for alternate cooperation with the presser foot B and a 4-motion top feed dog F. The top feed dog F operates in the opening 10 of the presser foot B and is supported on the frame arm 8 and is operatively connected to the main shaft 11 in the usual manner. This feed dog operates in rear of the needle path and cooperates with the work clamp E 40 to intermittently feed the fabric rearwardly when the needle is out of said fabric. The work clamp E cooperates with the bottom of the foot B to clamp the fabric therebetween during the idle motions of the feed dog F whereby said fabric 45 will be held against the thrust of the needle.

The work support C is capable normally of a small free upward and downward movement about its pivot 20 to permit not only a variation in the thicknesses of materials being stitched 50 but also to permit seams being fed over the ridge forming disc D. To this end, the work support C is provided with depending integral front and rear walls 37, 38 respectively arranged on opposite sides of the disc operating shaft 27. A head 55 39 includes an attaching plate 40 and a depending tubular neck 41 having an open lower end. The head 39 is rigidly attached to the lower edges of the depending walls 37, 38 by screws 42, 42. Mounted in said neck for vertical movements relative thereto is a core or support 43. A limiting screw 44 passes downwardly through a non-threaded opening 45 formed in the plate 40, the lower end of the screw being threaded into the core 43 and the head 46 of said screw 60 cooperating with the plate 40 to limit the upward movement of the work support C relative to the core or support 43. The upper surface of the core is normally spaced below the plate 40 and the upper portion of the core is reduced to form 70 a resultant peripheral recess for receiving a coil spring 47 which engages the bottom wall of the recess and the plate 40 and functions to yieldably retain the work support C against downward movement relative to said core.

The core 43 is normally locked against vertical movements, but when the core is moved vertically the work support C, the disc D, and the work clamp E are moved with it. The lower end of the core 43 is provided with a depending lug 48. A toggle is connected to the lug 48 and to the base 5 of the main frame. The toggle includes a bell crank lever 49 which includes an arm 50, normally disposed in a generally vertical position, and a forwardly extending generally horizontal arm 51. The lower end of the arm 50 is fulcrumed on an eccentric 52 which is fixed to a horizontal shaft 53, the latter being supported in the base 5 as shown in Figures 4, 6 and 8. The ends of the shaft 53 are journaled in the base 5 below the upper surface thereof. A normally vertically disposed link 54 is pivotally connected at its upper end by a pin 55 to the lug 48 and at its lower end by a pin 56 to the upper end of the toggle arm 50, the pin 56 being rigidly secured to the link 54 by a set screw 57. A coil spring 58 is disposed around the projecting end of the pin 56, one end of the spring being anchored in a transverse slot 59 formed in the outer end of the pin and the other end of the spring engaging under a stop pin 60 fixed to the bell crank 49. The spring 58 functions to yieldably retain the toggle elements 50, 54 in their extended or locked positions as shown in Figure 8, and a stop shoulder 61 fixed to the arm 50 cooperates with the stop shoulder 62 on the bottom of the link 54 to prevent the toggle elements passing beyond their locked positions. It will be noted that the arm 50 and the link 54, when in their normal or locked positions, are in general longitudinal alignment, i. e., the pivots 55, 56 and 53 are in alignment in a plane which is slightly inclined to the vertical, or in other words, in a plane at right angles to the plane of the foot B. A chain 63 which is adapted to be connected to a treadle or knee-press, has its upper end connected to the forward end of the arm 51 of said bell crank lever. Thus upon operation of the knee-press or treadle the toggle will be broken and the support or core 43 together with the work support C and parts mounted thereon, will be depressed to permit the ready insertion or withdrawal of the material, and upon release of said knee-press or treadle, the parts will be returned to their normal position by the spring 58. It will, therefore, be seen that when the toggle is in its locked or normal position, the work support C is capable of having a slight downward movement against the tension of the spring 47 so as to permit various thicknesses of fabrics and seams being fed through the machine.

In order to positively adjust the normal position of the work support C together with the disc D, and thereby set the machine for materials of different thicknesses, I have provided a hand adjusting shaft 64 which is journaled in a bushing 65 mounted in a tubular bearing bracket 66 secured in an opening formed in the front wall of the standard 6. A finger knob 67 is rigidly attached to the front end of the shaft 64 and a spring pressed pin 68 cooperates with the knob to retain the shaft in any position of adjustment. Journaled on the bracket 66 is a worm wheel 69 which is in constant mesh with a worm 70 formed on the inner end of the shaft 64. Journaled in the base 5 is a horizontal rock shaft 71 having a rock arm 72 fixed to its right hand end, said arm being pivotally connected by a link 73 to the worm wheel 69. The other end of the rock shaft 71 is provided with a rock arm 74 which is pivotally connected to the rear end of a

rack bar 75 which extends forwardly along the base to a point below and in front of the eccentric carrying shaft 53. The rack bar 75 is provided along its upper forward edge with rack teeth 76 which engage the teeth of a pinion 77 fixed on said shaft 53. A disc 78 is journaled on the shaft 53 and is provided with a pin 79 forming a support for the front end of said rack bar. A coil spring 80 is connected at one end to the disc 78 and at its other end to the base 5 and functions to urge the pin 79 upwardly whereby the rack bar will be retained yieldably in engagement with the pinion 77. It will, therefore, be seen that when the knob 67 is rotated the rack bar 75 will be moved endwise, the shaft 53 together with the eccentric 52 will be rotated, and the work support will be raised or lowered, depending on the direction of rotation of the knob.

The ridge forming element D is reciprocated from the main shaft 11 by a train of mechanism including a manually control lever whereby either the high or low portions 33, 36 of the disc or element will be alternately presented to the needle to thereby form alternate "anchor" and "skip" stitches in the material or whereby the high portion 33 only of the disc or element will be successively presented to the needle to thereby form successive "anchor" stitches in the material. To this end, a bell crank lever 81 is journaled on a horizontal axis 82 in the standard 6 and below the main shaft 11. The bell crank lever 81 includes a forwardly extending horizontal arm 83 which is connected by a link 85 to the main shaft 11 through the medium of a 2-to-1 reduction gear coupling which is indicated as a whole by the numeral 86 and which is fully shown and described in my prior Patent 1,989,602 referred to above. The bell crank lever 81 includes a depending arm 87 which is pivotally connected as at 88 to the rear end of a forwardly extending link 89. A horizontal shaft 90 is journaled in a base lug or post 91 at a point between the pivot shaft 20 of the work support C and the disc operating shaft 27, said shaft 90 being disposed in parallelism with said shafts 20 and 27. Fixed to the left hand end of the shaft 90 is an eccentric pin 92 and a lever 93 is journaled intermediate its ends on said eccentric pin. The lower arm 94 of said lever is pivotally connected as at 95 to the forward end of the link 89 and the upper arm 96 of said lever is pivotally connected as at 97 to a rearwardly extending link 98 which is pivotally connected at its rear end as at 99 to a depending rock arm 100 clamped to the disc operating shaft 27. Fixed to the left hand end of the eccentric shaft 90 is an upwardly extending rock arm 101 and pivotally connected to the upper end of said arm as at 102 is a rearwardly extending link 103, the rear end of said link being pivotally connected as at 104 to the lower end of a manually operable control lever 105 which is fulcrumed on the disc operating shaft 27 and has its upper end provided with a finger-piece or knob 106 which projects through an opening 107 formed in the work support C. The knob 106 also projects upwardly through a slot 108 formed in a plate 109 mounted on the upper surface of the work support C.

It will be noted that the eccentric pin 92 constitutes a shiftable fulcrum for the lever 93 and that when the shaft 90 is oscillated by the manually control lever 105 said fulcrum will be shifted either forwardly or rearwardly and the disc operating shaft 27 will be angularly shifted thereby, and consequently the disc D will be shifted

angularly with respect to the needle path. The driving connections between the main shaft 11 and the disc operating shaft 27 are such that the disc D will partake of a greater angular movement during alternate rearward strokes thereof and a lesser angular movement during intermediate rearward strokes. Thus when the manually control lever 105 is in the position shown in Figure 10^a the high peripheral portion 33 of the disc D will be presented to the needle during successive rearward movements of the disc whereby successive "anchor" stitches will be formed in the fabric; and when the control lever is in the position shown in Figure 11^a the high and low peripheral portions 33, 36 will be alternately presented to the needle whereby alternate "anchor" and "skip" stitches will be formed in the fabric. It will furthermore be observed that when the work support C is in its normal or locked position said support is capable of having a slight downward movement due to the intermediate spring 47, and that by reason of the lever 93 being disposed between the pivot shaft 20 of the work support and the disc operating lever 27 together with the link 98 which connects the lever 93 with the rock arm 103, this slight downward movement of the work support will maintain the low peripheral portion 36 of the disc D in proper cooperative relation to the needle path whenever said low portion 36 is positioned in cooperative relation with the needle and consequently the stitches will be properly positioned in the fabric.

It is of course to be understood that the details of structure and arrangement of parts may be variously changed and modified without departing from the spirit and scope of my invention.

I claim:

1. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a work support mounted on the base to swing upwardly and downwardly relative to the foot and about a horizontal axis located in rear of the needle, means for normally retaining the work support yieldably against depression, a reciprocating ridge forming element operating in the presser foot opening for projecting a ridge of fabric upwardly into needle penetrating position and movable upwardly and downwardly with said work support, an oscillatory shaft journaled on the work support and disposed in parallelism with the axis thereof and operatively connected to said element, and driving connections between the main and oscillatory shafts for operating the latter and including devices for retaining the oscillatory shaft against angular movement upon depression of the work support.

2. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a work support mounted on the base to swing upwardly and downwardly relative to the foot

and about a horizontal axis located in rear of the needle, means for normally retaining the work support yieldably against depression, an oscillatory ridge forming disc operating in the presser foot opening for projecting a ridge of fabric upwardly into needle penetrating position and movable upwardly and downwardly with said work support, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support.

3. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a work support mounted on the base to swing upwardly and downwardly relative to the foot and about a horizontal axis located in rear of the needle, means for normally retaining the work support yieldably against depression, an oscillatory ridge forming disc operating in the presser foot opening for projecting a ridge of fabric upwardly into needle penetrating position and movable upwardly and downwardly with said work support, said disc having high and low peripheral work presenting portions arranged in tandem, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support, said driving connections periodically presenting to the needle first one of said disc portions and then the other to thereby vary the effective depths of the needle penetrations.

4. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a work support mounted on the base to swing upwardly and downwardly relative to the foot and about a horizontal axis located in rear of the needle, means for normally retaining the work support yieldably against depression, a reciprocating ridge forming element operating in the presser foot opening for projecting a ridge of fabric upwardly into needle penetrating position and movable upwardly and downwardly with said work support, an oscillatory shaft journaled on the work support and disposed in parallelism with the axis thereof and operatively connected to said element, and driving connections between the main and oscillatory shafts for operating the latter and including devices for retaining the oscillatory shaft against angular movement upon depression of the work support, said devices including a lever fulcrumed on an axis located intermediate the work support pivot and the

oscillatory shaft, a rock arm fixed to the oscillatory shaft, and a link connecting the lever and the rock arm.

5. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a work support mounted on the base to swing upwardly and downwardly relative to the foot and about a horizontal axis located in rear of the needle, means for normally retaining the work support yieldably against depression, an oscillatory ridge forming disc operating in the presser foot opening for projecting a ridge of fabric upwardly into needle penetrating position and movable upwardly and downwardly with said work support, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support, said devices including a lever fulcrumed on an axis located intermediate the work support pivot and the oscillatory shaft, a rock arm fixed to the oscillatory shaft, and a link connecting the lever and the rock arm.

6. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a work support mounted on the base to swing upwardly and downwardly relative to the foot and about a horizontal axis located in rear of the needle, means for normally retaining the work support yieldably against depression, an oscillatory ridge forming disc operating in the presser foot opening for projecting a ridge of fabric upwardly into needle penetrating position and movable upwardly and downwardly with said work support, said disc having high and low peripheral work presenting portions arranged in tandem, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support, said driving connections periodically presenting to the needle first one of said disc portions and then the other to thereby vary the effective depths of the needle penetrations, said devices including a lever fulcrumed on an axis located intermediate the work support pivot and the oscillatory shaft, a rock arm fixed to the oscillatory shaft, and a link connecting the lever and the rock arm.

7. In a blind stitch sewing machine, the combination with a frame including a base and a forwardly extending arm, of a presser foot rigidly attached to the free end of said arm, a work support mounted on the base to swing about a horizontal axis located in rear of the foot and

having a portion disposed under said foot, an upwardly and downwardly movable support for the work support, yieldable means located between the movable support and the work support for permitting a limited downward movement of the work support relative to the foot, releasable locking means between the movable support and the base for normally retaining said movable support against downward movement, and manually operable means connected to said locking means for raising or lowering said locking means together with said movable support.

8. In a blind stitch sewing machine, the combination with a frame including a base and a forwardly extending arm, of a presser foot rigidly attached to the free end of said arm, a work support mounted on the base to swing about a horizontal axis located in rear of the foot and having a portion disposed under said foot, an upwardly and downwardly movable support for the work support, yieldable means located between the movable support and the work support for permitting a limited downward movement of the work support relative to the foot, releasable locking means between the movable support and the base for normally retaining said movable support against downward movement, said locking means including an eccentric journaled on the base, and a toggle connection between the movable support and the eccentric, and manually operable means connected to said eccentric for rotating the latter to effect the raising or the lowering of said toggle connection together with said movable support.

9. In a blind stitch sewing machine, the combination with a frame including a base, a standard, and an arm extending forwardly from the upper end of the standard, of a presser foot rigidly attached to the free end of said arm, a work support mounted on the base to swing about a horizontal axis located in rear of the foot and having a portion disposed under said foot, an upwardly and downwardly movable support for the work support, yieldable means located between the movable support and the work support for permitting a limited downward movement of the work support relative to the foot, releasable locking means between the movable support and the base for normally retaining said movable support against downward movement, and means connected to said locking means and including a manually operable control element mounted on the standard for raising or lowering said locking means together with said movable support.

10. In a blind stitch sewing machine, the combination with a frame including a base, a standard, and an arm extending forwardly from the upper end of the standard, of a presser foot rigidly attached to the free end of said arm, a work support mounted on the base to swing about a horizontal axis located in rear of the foot and having a portion disposed under said foot, an upwardly and downwardly movable support for the work support, yieldable means located between the movable support and the work support for permitting a limited downward movement of the work support relative to the foot, releasable locking means between the movable support and the base for normally retaining said movable support against downward movement, said locking means including an eccentric journaled on the base, and a toggle connection between the movable support and the eccentric, and manually operable means connected to said eccentric for rotating the latter to effect the raising or lowering

of said toggle connection together with said movable support, said manually operable means including a pinion fixed to the eccentric to rotate therewith, a rack bar slidably mounted on the base and engageable with the pinion, a manually operable element mounted on the main frame, and connections between said element and said rack bar for operating the latter.

11. In a sewing machine, the combination of a main frame including a base, a standard, and an arm extending forwardly and downwardly relative to the base from the upper end of the standard; and a work support mounted on the base and having a portion disposed in a plane below the free end of said frame arm, said work support being fulcrumed on a horizontal axis to swing upwardly and downwardly relative to said arm, said axis being disposed in a plane at right

angles to the longitudinal axis of said arm and in rear of the free end of said arm.

12. In a sewing machine, the combination of a main frame including a base, a standard, and an arm extending laterally from the upper end of the standard and terminating in an arm extending forwardly and downwardly relative to the base; and a work support mounted on the base in front of the laterally extending arm and having a portion disposed in a plane below the free end of said forwardly extending arm, said work support being fulcrumed on a horizontal axis to swing upwardly and downwardly relative to said free end, said axis being disposed in a plane at right angles to the longitudinal axis of said forwardly extending arm and in rear of the free end of said arm.

CHARLES W. MUELLER.
